UNITED STATES PATENT OFFICE.

KARL STAHLGREN, OF SALINAS, CALIFORNIA.

MINERAL-EXTRACTING MACHINE.

SPECIFICATION forming part of Letters Patent No. 631,680, dated August 22, 1899.

Application filed July 9, 1898. Serial No. 688,510. (No model.)

To all whom it may concern:

Be it known that I, KARL STAHLGREN, a citizen of the United States, residing at Salinas city, county of Monterey, and State of California, have invented certain new and useful Improvements in Mineral-Extracting Machines; and I hereby declare the following to be a full, clear, and exact description of the same, reference being had to the accompanying drawings, forming a part of this specification.

My invention relates to the procuration of precious metals, especially gold, from silicious or other matter with which it is associated or incorporated by processes commonly called "concentration" and "amalgamation" and to a novel means of applying these, as hereinafter explained.

My improvements consist in devices where-by the comminuted ore containing gold, silver, or other valuable metals mixed with water, commonly called "pulp," is subjected to a high degree of centrifugal force and at the same time disposed in a thin annular stratum and caused to flow over silver-coated surfaces, plain or corrugated, collecting the gold amalgamated with mercury thereon, such devices consisting of a revolute open-top vessel provided with a removable lining, means to impel this vessel and to supply and discharge the water and ore, also in other devices accessory thereto.

The objects of my invention are to perform the process of separation and amalgamation continuously in an effective and rapid manner within small space with inexpensive apparatus and without the exercise of special skill on the part of attendants.

To these ends I provide apparatus as illustrated in the drawings, herewith forming a part of this specification, in which—

Figure I is a central vertical section through a concentrating and amalgamating machine constructed according to my invention, and Fig. II is a plan view of the same machine with a portion of the top cover and supply-way removed.

Similar numerals of reference indicate corresponding parts in both figures of the drawings.

The main supporting-frame 1 consists of the usual vertical and cross members, the cross-

girths 2, 3, and 4 being provided with bearings 5, 6, and 7 for the main and driving spindles 8 and 9. The driving-spindle 9 is provided with a pulley 10 to receive a band and is flexibly connected to the main or upper spindle 8 by a universal joint at 11 for purposes hereinafter explained.

On the top of the main spindle 8 is mounted an open-top vessel 12, attached to a flange 13 on the spindle 8, made of strong metal to safely resist a high speed of rotation and consequent centrifugal strain.

Surrounding and protecting the revolving vessel 12 is a circular chamber 14, formed by the shell 15, which can be made integral with the main frame 1 or can be separate and attached thereto.

Concentric with the chamber 14 is a second and larger circular chamber 16, formed by the vessel 17, preferably made integral with the shell or member 15 and provided with removable cover 18; in which is formed a receiving-nozzle 19, as seen in Fig. I.

Pendent from the covering-plate 18 is a tube 20, that can be made integral, as shown, or separately and attached by a flange at the top. This tube 20 extends down near the bottom of the vessel 12, at one side of which is a discharge-spout 21, through which water and sand or pulp escape after treatment.

Within the rotating vessel 12 I place a removable vessel or lining 22, made of thin metal, preferably of copper or some alloy that can be electroplated with silver on its interior, so as to better resist the action of corrosive elements in the ore treated, also to cause an affinity for mercury or amalgam. This lining 22, which may be called the "amalgamating" vessel, is by preference left open at the bottom to facilitate cleaning and has at its top an outward curved flange 23, as indicated by arrows in Fig. I. The material after being discharged over this flange 23 impinges against an annular curtain 24, supported by an outward-turned flange 25 under the cover 18 and at its bottom an inward-turned flange 26, as seen in the drawings.

In the bottom of the chamber 16 I place an annular pan 27, having riffles 28, that prevent circulation and tend to arrest and precipitate any metal that has passed the anterior amalgamating surfaces.

The operation is as follows: A charge of quicksilver is placed in the vessel 22 or in other places of catchment, as in the vessel 24 and pan 27, or can be fed in with the material to be treated. The vessel 12 is set in rapid revolution by means of the driving-spindle 9 and tends to assume a theoretical center of gyration, permitted by the flexible joint at 11 and spherical bearing 5. Material is then run into the inlet-way 19 from a spout 29, or in any other suitable manner, falls down through the tube 20, and being there set in revolution is by centrifugal force disposed in a thin annular sheet within the amalgamating vessel flows upward over the corrugated surface 31, out over the flange 23 into the annular vessel 24, out of that vessel down into the pan 27, and then overflows through the spout 21.

The removable lining 22 can be made with a smooth instead of a corrugated surface, or the corrugations can be angular, curved, deep, or shallow, as the nature of the material and the velocity of movement demands. Ruffles 28 can be placed in the bottom of the vessel 24 and other modifications made without materially departing from the nature and objects of my invention.

To clean the metal-catching surfaces, it will be seen that all of these are removable, not even requiring fastening, and by providing duplicates for substitution the process can go on without interruption. It will also be seen that by this manner of operating each particle of material is independently acted upon by a high degree of centrifugal force in proportion to its weight transversely through a thin film when passing over the interior of the vessel 22, then impinges violently in a diffused state around the interior of the vessel 24, settles and overflows from there into the pan 27 to settle again, all the time in contact with catchment surfaces.

Having thus explained the nature and objects of my invention and the manner of ap-

plying the same, what I claim as new, and desire to secure by Letters Patent, is—

1. In a centrifugal mineral-extractor, in combination, a revolute vessel with cylindrical vertical wall and means for rotating the same, an exterior stationary vessel having a cylindrical wall concentric with the wall of said revolute vessel, an annular chamber surrounding said exterior stationary vessel, extending above the same and forming a part thereof, having an outlet-passage, a cover secured upon said annular chamber, provided with a central receiving-nozzle and a depending cylindrical wall continuous with said nozzle, said depending wall extending within said revolute vessel to near its bottom, a depending cylindrical curtain within said annular chamber exterior to and concentric with said stationary and revolute vessels, and a removable lining within said revolute vessel, extending to and over the top of both the revolute and the said exterior stationary vessel in a curved lip or flange, substantially as specified.

2. In a centrifugal mineral-extractor, in combination, a stationary cylindrical vessel, provided with an annular outer chamber surrounding the same, a cover for said vessel, having a central receiving-nozzle and depending cylindrical tube concentric with said stationary cylindrical vessel, an annular removable pan in the bottom of said annular outer chamber, an annular depending curtain 24 having inturned flange 26, a revolute cylindrical vessel within said stationary vessel and concentric therewith, means for rotating said revolute vessel on its true axis of mass, and a removable thin metal lining, outturned at top, within said revolute vessel, all substantially as specified.

KARL STAHLGREN.
